UNITED STATES PATENT OFFICE.

EDWIN T. GORHAM, OF GRAND RAPIDS, MICHIGAN, ASSIGNOR TO WILMARSH & MORMAN COMPANY, OF GRAND RAPIDS, MICHIGAN, A CORPORATION OF MICHIGAN.

CUTTER-GRINDER.

1,295,156.

Specification of Letters Patent. Patented Feb. 25, 1919.

Application filed July 5, 1917. Serial No. 178,700.

To all whom it may concern:

Be it known that I, EDWIN T. GORHAM, a citizen of the United States, residing at Grand Rapids, county of Kent, State of Michigan, have invented certain new and useful Improvements in Cutter-Grinders, of which the following is a specification.

This invention relates to improvements in cutter grinders.

10 The objects of the invention are:

First, to provide an attachment for a grinding machine by means of which the faces of the teeth of a cutter which is to be ground may be easily, quickly and accurately alined with the face of the grinding disk.

Second, to provide means whereby the depth of the cut may be quickly and accurately regulated.

Third, to so construct the means for regulating the depth of the cut that it may be displaced from the path of the teeth to allow a new tooth to be brought into position to be ground.

Further objects, and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing, forming a part of this specification, in which:

35 Figure I is a detail perspective view of the head, and bed, of a grinding machine, showing my improved cutter grinding attachment.

40 Fig. II is a plan view of my improved cutter grinding attachment, the positions of the grinding disk, face aliners and cut regulators, during certain operations, being shown in dotted lines and in full lines.

45 Fig. III is an enlarged detail section, taken on a line corresponding to line 3—3 of Fig. II.

Fig. IV is an enlarged detail section, taken on a line corresponding to line 4—4 of Figs. II and III.

50 Fig. V is an enlarged detail section taken on a line corresponding to line 5—5 of Figs. III and IV.

Fig. VI is a rear side elevation of my improved attachment, showing details of the

supporting means for the face alining device.

Fig. VII is an enlarged detail section taken on a line 7—7 of Fig. II.

In the drawing similar reference characters refer to similar parts throughout the several views, and the sectional views are taken looking in the direction of the little arrows at the ends of the section lines.

Referring to the drawing, the reference character 1 indicates the reciprocating bed of a grinding machine and 2 the head thereof. The head comprises the spindle 3 upon which is mounted the grinding disk 4. This grinding disk, as shown in Fig. II, is provided with a flat face 5. The base 6 of my grinding attachment is secured to the reciprocating bed 1 by means of the bolts 7, which are engaged in the slots 8. A stepped cutter arbor 9 is vertically journaled in the base 6 and is provided with a nut 10 for securing the cutters to be ground. The stepped arbor is designed to receive and hold cutters having different sized openings.

In operation the arbor 9 and the grinding cutting disk 4 are adjusted relative to each other in such a manner that the axis of the arbor 9 lies in the plane of the cutting face of the grinding disk 4, as shown in Fig. II. This insures the grinding of the teeth on the proper radii.

85 Mounted on the rear side of the base 6 is an upwardly extending arm 11, the arm being slotted at 12 to receive the supporting bolt 13, the bolt being provided with a clamping nut 14, so that the arm may be adjusted in a plane parallel to the grinding disk or wheel.

On the upper end of the arm 11 is an alining stop 15 adapted to be adjusted into engagement with the face of a tooth of a cutter mounted upon the arbor, as shown in Fig. II, or swung out of the way, as shown by dotted lines in Fig. II, or adjusted close to the disk so that its end may be alined with the cutting face thereof.

100 On the forward side of the base 6 is a slotted bracket 17 carrying a post 18. The post 18 is adjustably secured in the slot of this bracket so that the post may be adjusted laterally. This post carries an arm 19 adjustably secured thereon by means of the clamp 20.

A gage holder 21 is pivotally secured to

the outer end of the arm 19 by means of the pivot 22. The holder is provided with a stop 23 which coacts with the end of the arm to limit the swing of the holder toward the 5 arbor 9. A spring 24, one end of which is secured to the arm and the other to the holder, yieldingly holds the holder toward the arbor.

The gage 25 is mounted for longitudinal 10 adjustment in the holder. An adjusting screw 26 is arranged longitudinally of the holder and threaded into the gage for adjustment thereof. The gage is bent inwardly toward the arbor, as shown in Fig. 15 II, to coact with the rear sides of the cutter teeth.

A screw 28 is disposed through the side 20 of the holder to coact with the longitudinal groove 29 in the gage preventing its rotation. The set screw 30 secures the gage in its adjusted position.

In operation, the cutter to be ground is mounted upon the arbor. The alining stop 15 is then adjusted to alinement with the 25 grinding face of the disk and then to the face of one of the teeth of the cutter to be ground, as shown in Fig. II.

The post 18, arm 19 and gage 25 are then 30 adjusted to bring the gage into contact with the rear of the tooth engaged by the stop, as shown in Fig. III. The alining stop is then thrown out of the way and the gage adjusted to regulate the amount or depth of cut.

35 With the parts thus adjusted they are ready for the grinding operation.

As the bed is reciprocated the teeth are brought into grinding position relative to the grinding disk and the desired cut taken 40 therefrom. As the cutter is turned by the operator the teeth are successively brought to position.

With the parts thus arranged I greatly facilitate the work of grinding rotary cutters, not only increasing the output but improving the same as, by the aid of my attachment, very accurate grinding may be easily done.

I have not attempted to illustrate or 50 scribe certain modifications contemplated by me, as I believe the disclosure made will enable those skilled in the art to which my invention relates to embody or adapt the same as may be desired.

55 Having thus described my invention, what I claim as new and desire to secure by Letters Patent, is:

1. The combination with a grinding machine comprising a reciprocating bed and a 60 grinding disk, of a base member carried by said bed and provided with a laterally extending slotted bracket and an arbor for the cutters to be ground, means for securing a cutter to said arbor, a feed gage supporting post adjustable in said slot of said

bracket, an arm on said post, a gage holder pivotally mounted on said arm, a gage mounted in said holder for longitudinal adjustment, an adjusting screw for said gage, a set screw for securing said gage in adjusted position in said holder, a spring secured to said arm and said holder for yieldingly supporting said gage in cutter engaging position, an alining stop supporting arm adjustably mounted on said base, and an 75 alining stop adjustable on said arm to be alined with the face of the grinding disk or engaged with the face of the cutter teeth.

2. The combination with a grinding machine comprising a reciprocating bed and 80 a grinding disk, of a base member carried by said bed and provided with a laterally extending slotted bracket and an arbor for the cutters to be ground, means for securing a cutter to said arbor, a feed gage supporting post adjustable in said slot of said bracket, an arm on said post, a gage holder pivotally mounted on said arm, a gage mounted in said holder for longitudinal adjustment, an adjusting screw for said gage, 90 a set screw for securing said gage in adjusted position in said holder, a spring secured to said arm and said holder for yieldingly supporting said gage in cutter engaging position.

3. The combination with a grinding machine comprising a reciprocating bed and a grinding disk, of a base member carried by said bed and provided with an arbor for the cutters to be ground, means for securing a cutter to said arbor, a feed gage supporting post mounted on said base, an arm on 100 said post, a gage holder pivotally mounted on said arm, a gage mounted in said holder for longitudinal adjustment, a spring secured to said arm and said holder for yieldingly supporting said gage in cutter engaging position, an alining stop supporting arm adjustably mounted on said base, and an 105 alining stop adjustable on said arm to be alined with the face of the grinding disk or engaged with the face of the cutter teeth.

4. The combination with a grinding machine comprising a reciprocating bed and a grinding disk, of a base member carried by 115 said bed and provided with an arbor for the cutters to be ground, means for securing a cutter to said arbor, a feed gage supporting post mounted on said base, an arm on said post, a gage holder pivotally mounted on said arm, a gage mounted in said holder for longitudinal adjustment, a spring secured to said arm and said holder for yieldingly supporting said gage in cutter engaging position.

5. The combination with a grinding machine comprising a reciprocating bed and a grinding disk, of a base member carried by said bed and carrying an arbor for the cutters to be ground, a feed gage support ad- 120

justably mounted on said base, a gage holder pivotally mounted on said support, a gage mounted in said holder for longitudinal adjustment, a spring for urging said gage to cutter engaging position, and an alining stop, all coacting for the purpose specified.

6. An attachment for grinding machines comprising a base adapted to be mounted upon the bed of the grinding machine and provided with an arbor for the cutters to be ground, an alining stop adjustably secured to the base and adapted to be swung into and out of engagement with the face

5

10

of the teeth of the cutter, an adjustable feed gage pivotally mounted on the base to coact 15 with the rear faces of the teeth of a cutter to be ground, and means for adjusting said gage.

In witness whereof, I have hereunto set my hand and seal in the presence of two 20 witnesses.
